UNITED STATES PATENT OFFICE.

CHARLES JASON GREENSTREET, OF WEBSTER GROVES, MISSOURI.

FUEL-FEEDING DEVICE FOR FURNACES.

1,132,715.

Specification of Letters Patent. Patented Mar. 23, 1915.

Application filed March 20, 1914. Serial No. 826,002.

To all whom it may concern:

Be it known that I, CHARLES J. GREENSTREET, a citizen of the United States, and a resident of the city of Webster Groves, in the county of St. Louis and State of Missouri, have invented a new and useful Improvement in Fuel-Feeding Devices for Furnaces, of which the following is a specification.

10 This invention relates particularly to devices for feeding coal dust and small particles of coal to furnaces of all kinds.

The object of the invention is to provide an apparatus for feeding such fuel and suitably commingling it with air, whereby it may be conducted to a furnace in the form of a combustible fluid.

Heretofore, efforts have been made to devise apparatus for utilizing coal dust or 20 comminuted particles of coal as a fuel for furnaces; but such devices have been unsatisfactory except in extensive plants. The device of my invention is peculiarly adapted to provide a uniform feed of comminuted 25 fuel to a fire box of limited capacity, whether the fire-box is stationary or installed upon a traveling vehicle; and this peculiar adaptability is due to the simplicity of the device, the small number of parts employed, and the storage, conveyance and 30 discharge of the powdered fuel by means of apparatus capable of close regulation through a wide range. By means of this invention, the combustible mixture is always subject 35 to exact control, which prevents the irregular combustion and intermittent explosions incident to the use of comminuted fuel and which sometimes cause accidental premature ignition of the highly combustible product; 40 and hence the invention eliminates the danger of explosion which has heretofore been a deterrent to the use of such fuel in traveling vehicles.

In the accompanying drawings, which 45 form part of this specification, and wherein like parts are designated by like symbols in the several views, Figure 1 is a side elevation of apparatus embodying my invention; Fig. 2 is a rear end view of said apparatus; 50 Fig. 3 is a side elevation of the fuel measuring and feeding device drawn to a larger scale than Figs. 1 and 2; Fig. 4 is a vertical cross-section of the fuel feeding device on the line 4—4 of Fig. 3, looking from the 55 front of the device; Fig. 5 is a similar cross-section on the line 5—5 of Fig. 3; and Fig. 6

is a vertical longitudinal section of the device shown in Fig. 3 on the line 6—6 of Fig. 4, looking in the direction of the arrows.

As shown in Figs. 1 and 2 of the drawings, the apparatus comprises a fuel measuring and feeding device 11 having a discharge chute 12 for conducting the fuel into the intake duct 13 of the fan blower 14. The outlet duct 15 of the blower leads to a suitable nozzle or fuel opening in the fire box or furnace. The fuel measuring and feeding device 11 is supplied with comminuted fuel from a hopper 16 or other suitable means through an opening in its top, and its driving pulley 17 may be rotated from any suitable source of power.

The fuel feeding and measuring device comprises a casing having in its upper part a chamber 18 forming a fuel receiving receptacle, and in its lower part a chamber 19 for the fuel measuring, feeding and regulating mechanism. The bottom part of the upper chamber projects into the lower chamber and is fitted with sliding bottom doors or gates 20, which are adjustable horizontally to regulate the width of the opening between them. Rods 21 are secured to the bottom doors 20 and extend through the side walls of the casing for moving the bottom doors. The extremities of these rods are threaded and screwed into the threaded sleeves or ring nuts 22 which are grooved around the outside and mounted in brackets 23 secured on the outside of the casing. The sleeves 22 are knurled or roughened on the periphery to facilitate turning them by hand. Hence the position of the bottom doors can be readily adjusted, and the doors will remain in adjusted position without further clamping means being required.

Spaced below the adjustable doors is a fixed bottom 24 for the fuel receptacle 18, and the ends of the fixed bottom project beyond the end walls 25 of the fuel receptacle. 100 Elongated openings 26 are left beneath the end walls 25 immediately above the fixed bottom 24. An endless conveyer comprising endless chains 27 and flights 28 passes through the openings 26 and over the fixed bottom 24. Two grooves are made lengthwise of the bottom for the chains to run in, so that the lower edges of the flights scrape along on the fixed bottom. The vertical width of the flights is slightly less than the 105 vertical dimension of the space between the bottom doors 20 and fixed bottom 24. A

vertical slide 29 is adjustably mounted upon the front end wall of the fuel receptacle. The lower edge of the slide 29 is adapted to cover more or less of the opening 26, and 5 the slide thereby limits the vertical width of the opening and controls the thickness of the moving stream of fuel carried along by the conveyer flights. The lower end of a rod 30 is fixed to the slide 29. The upper 10 end of the rod is threaded and projects outside the casing. The projected threaded end goes through a bracket 31 fixed to the casing, and is provided with adjusting nuts 32 for fixing it in adjusted position. By adjusting the position of the slide the rate of 15 delivery of the fuel by the conveyer can be regulated to a nicety.

The conveyer chains 27 pass over sprocket wheels 33 rotatably mounted near the ends 20 of the chamber 19 on shafts 34, journaled in the side walls of the casing. One of the shafts 34 projects through the side wall of the casing and carries a toothed gear 35. Meshing with the gear wheel 35 is a toothed 25 pinion 36, which is mounted on the end of a shaft 37 which is journaled in the side walls of the casing. The shaft 37 extends clear through the casing and its opposite end carries the driving pulley 17, whereby the moving 30 parts of the device are continuously actuated. It is found that if the speed of the driving pulley and the sizes of the gears and sprockets are such as to cause the conveyer to move at a speed of from about three 35 to eight feet per minute, satisfactory results are secured.

About midway across the fuel receptacle an oscillating shaft 38 is journaled in the side walls of the casing. One end of this 40 shaft projects through the side wall and carries a downwardly extending lever arm 39 which is rigidly secured to the rocking shaft. The lower end of the lever arm 39 is connected to a link 40 by a pivot pin, and 45 the other end of the link is journaled on a crank pin on the outside of the gear wheel 35, whereby each rotation of the gear wheel causes the oscillating shaft to oscillate back and forth through a small angle. The oscillating shaft carries two double arms 41 or 50 blades which are rigidly fixed thereto, one on each side of the longitudinal center line of the fuel receptacle, and which continuously oscillate back and forth in vertical planes on each side of the opening between 55 the bottom doors. These moving blades prevent the fuel from arching over the bottom opening, and insure a continuous flow of fuel onto the fixed bottom.

60 The fixed bottom 24 is somewhat longer than the fuel receptacle 18, and its discharge end projects from beneath the bottom doors some distance in the direction of movement of the conveyer. Below the discharge end of the fixed bottom is an opening

in the bottom of the casing which leads to the chute 12. This opening extends substantially the full width of the casing, and the inclined lower wall of the chute 12 slopes downward from its upper end at one end of 70 the opening across the space below the opening to its lower end which is beyond the other end of the opening. The lower edge 42 of the lower wall of the chute 12 projects into the intake duct 13 of the blower, and terminates below the top wall of the intake. An air valve 43 is fitted to the end of the intake duct removed from the blower, for controlling the amount of air drawn beneath the lower edge 42 of the inclined 80 chute. An opening 44 in the rear end wall of the chamber 19 admits air beneath the fixed bottom which commingles with the falling fuel as it is discharged from the front end of the latter into the chute 12. The 85 width of the opening 44 can be adjusted by means of a slide 45 moved by a screw 46 which is mounted in the bracket 47 on the rear wall of the chamber 19. By turning the screw 46, the amount of air entering the 90 chamber 19 through the opening 44 can be controlled.

In the operation of the device the fuel, which is in the form of powder or finely divided particles, is fed to the receptacle 18 by any suitable means, and the blower and conveyer are set in motion. The bottom doors of the fuel receptacle are adjusted until the opening between them is sufficient to permit an unbroken column or stream of fuel to pass through onto the fixed bottom 24. The fuel does not fall freely, but it is checked by the fixed bottom, where it spreads out somewhat below the bottom doors in a loose pile. The pile of fuel on the fixed bottom is kept continuously moving by the flights, and this movement tends to spread the fuel sidewise and keep it from becoming packed hard by the weight of the fuel in the receptacle above the bottom doors. The projecting discharge end of the fixed bottom permits still further loosening up of the fuel being carried along by the flights, as there is no column of fuel above this portion of the bottom to pack the moving fuel pile. The inclined lower wall of the chute 12 tends to retard slightly the fuel striking it near its top, thus stringing out and equalizing the flow of fuel into the intake duct. 110

The width of the fuel pile on the fixed bottom can be controlled by the width of the opening between the bottom doors, and its thickness can be controlled by the vertical adjustment of the slide 29. Small changes 115 in the quantity of fuel which it is desired to feed per unit of time are most easily made by varying the vertical adjustment of the slide 29. Changes in the amount of air may be made by adjusting either the air valve 43 120

in the intake duct 13, or the slide 45 on the rear of the casing, or both simultaneously, as desired. The rate of feed of the fuel can be controlled also by changing the speed of 5 rotation of the driving pulley 17 by suitable means. Changes in the proportionate amount of moisture in the comminuted fuel have no effect on the rate of feeding of the fuel, for the reason that the dimensions of 10 the space between the bottom doors of the fuel receptacle are sufficient to insure an ample supply of fuel to the flights; and the bottom doors support the greater part of the weight of the fuel in the receptacle and 15 prevent changes therein from causing more or less dense packing of the fuel on the fixed bottom.

It is evident from the preceding description of the invention that it is not restricted to the exact form of the parts and arrangements thereof as shown in the drawings accompanying this specification; but the device shown and described herein is representative of the invention.

25 I claim the following as my invention:

1. A device for feeding comminuted fuel comprising a fuel storage receptacle with a bottom opening and a wide fixed bottom spaced below said opening, said bottom being of greater width than said opening whereby the fuel is banked up to fill said opening without covering said bottom, and means for moving fuel lengthwise on said fixed bottom, said fixed bottom projecting beyond said fuel receptacle in the direction of movement of said fuel moving means and constituting an open trough wherein the compacted fuel is loosened.

2. A device for feeding comminuted fuel comprising a fuel storage receptacle with a bottom opening and a wide fixed bottom spaced below said opening, means for varying the width of said opening, said bottom being of greater width than the greatest 15 width of said opening, and means for moving fuel lengthwise on said fixed bottom, said fixed bottom projecting beyond said fuel receptacle in the direction of movement of said fuel moving means and constituting 20 an open trough wherein the compacted fuel is loosened.

3. A device for feeding comminuted fuel comprising a fuel storage receptacle with a bottom opening, a wide flat discharge surface of greater width than the greatest 55 width of said bottom opening, said surface being below said bottom opening, means for moving fuel along said discharge surface, and a transversely arranged duct below the discharge end of said surface, said duct having an inclined lower wall sloping downwardly from one extremity of the discharge end of said surface to beyond the other extremity thereof whereby masses of fuel falling intermittently sidewise off of the end of 60 said discharge surface are transformed into 65 a continuous stream.

4. A device for feeding comminuted fuel comprising a fuel storage receptacle with a wide fixed bottom and elongated transverse 70 openings at its ends, one of the ends of said bottom being extended beyond said receptacle to form a flat discharge surface, means for moving fuel along said discharge surface, and a transversely arranged duct below the discharge end of said surface, said duct having an inclined lower wall sloping downwardly from one extremity of the discharge end of said surface to beyond the other extremity thereof whereby masses of 80 fuel falling intermittently sidewise off of the end of said discharge surface are transformed into a continuous stream.

5. A device for feeding comminuted fuel comprising a fuel storage receptacle having 85 a discharge opening lengthwise of its bottom, the bottom of said receptacle being longer than its top and its end walls diverging downwardly, means below said opening for checking the flow of fuel through said 90 opening, means for moving the fuel below said opening lengthwise thereof, and means above said opening having movement lengthwise thereof whereby the fuel is prevented from bridging over said opening.

Signed at St. Louis, Missouri, this 17th day of March, 1914.

CHARLES JASON GREENSTREET.
